UNITED STATES PATENT OFFICE.

OTTO ANDREAS ANDERSON, OF CHICAGO, ILLINOIS, ASSIGNOR TO ZANGERLE & PETERSON COMPANY, OF CHICAGO, ILLINOIS, A CORPORATION OF ILLINOIS.

DESIGN FOR A SETTEE FRAME OR SIMILAR ARTICLE.

Application filed November 7, 1928. Serial No. 28,795. Term of patent 3½ years.

To all whom it may concern:

Be it known that I, OTTO ANDREAS ANDERSON, a citizen of the United States, residing at Chicago, in the county of Cook and State of Illinois, have invented a new, original, and ornamental Design for a Settee Frame or Similar Article, of which the following is a specification, reference being had to the accompanying drawing, forming a part thereof.

The figure is a perspective view of a settee frame or similar article showing my new design.

The ornamentation shown is continued around the lower end of the frame.

I claim:

The ornamental design for a settee frame or similar article as shown and described.

In witness whereof, I hereunto subscribe my name, this 2 day of Nov., 1928.

OTTO ANDREAS ANDERSON.
